EDGE TRIM FOR CURTAINS OR THE LIKE

Lorance R. Wright, Memphis, Tenn., assignor to
 The Fashion Curtain Company, Inc., Memphis,
 Tenn., a corporation of Tennessee

Application November 22, 1940, Serial No. 366,525

1 Claim. (Cl. 156—10)

This invention relates primarily to ruffled edge-trims for curtains or the like, though it may be applied to fabric structures for other purposes.

It further relates to the method of assembling and securing together the materials and parts which form such structures in a manner which permits extremely rapid large scale operation and produces a desirable and satisfactory product.

The objects of the invention are:

To arrange and secure along the edge of a fabric structure, such as a curtain or drape, a trim having both edges ruffled and which trim is so secured to the fabric section that the trim satisfactorily hides the raw edge of the fabric and the fabric in turn hides the raw edge of the trim itself.

A further object of the invention is to provide a method of assembling a trim along a fabric edge which includes approaching the raw edges of a body fabric and a ruffle fabric to a stitching mechanism and so guiding and folding the two fabrics and tucking and stitching them together as to produce a structure with a double tucked finish for the body fabric edge.

The means by which the foregoing and other objects are accomplished will readily be understood from the following specification upon reference to the accompanying drawing, in which:

Fig. 1 is an elevation of a corner portion of a fabric structure, such as a curtain, showing the ruffled edge gathered and secured thereto.

Fig. 2 is a single line section taken as on the line II—II of Fig. 1.

Fig. 3 is an enlarged view of the same section; and

Fig. 4 a view, relatively reversed with regard to Fig. 1, showing fragmentary portions of the body and ruffle fabrics and the manner in which they are folded, approached and stitched together.

Referring now to the drawing in which the various parts are indicated by numerals:

11 is the body fabric or body as of a curtain, and 13 a ruffle forming an ornamental edge for said body. The ruffle 13, as shown in Fig. 3, preferably has one edge folded backwardly and turned inwardly to form a finished hem 15 along its skirt 16 and a deep flap 17 along the opposite edge backwardly folded to form a heading 19, the flap 17 usually having a raw edge. The body 11 has a relatively narrow forwardly folded edge portion or flap 21, also usually with a raw edge. The curtain body and the ruffle are assembled with their backward and forward flaps 21 and 19 respectively abutting in overlapping relation, the

raw edge of the flap 17 being adjacent, but spaced slightly away from the fold line 23 of the body and its flap 21, the ruffle being secured to the body by lines of stitching 25, 27, spaced apart 5 slightly less than the width of the flap 21, and lying respectively along the raw edge of the backwardly folded flap 17 of the ruffle heading, and the raw edge of the forwardly folded flap 21 of the body 11.

10 The ruffle 13, including the heading flap 19, is tucked or gathered at 29 along the stitching lines 25, 27 and relative to the body 11 and its flap 21, to accomplish the ruffling, the stitching holding the ruffle to the body portion and effectually 15 concealing the raw edges of the flaps 19 and 21, the resulting ruffled edge fabric structure being of unusually pleasing design and accomplished from two pieces only of material.

The method of accomplishing the ruffled edge fabric structure is in part indicated in Fig. 4. In 20 this figure, which is about twice the scale of and is reversed relatively to Fig. 1, 11—A is a fragmentary portion of the body which is being approached to means (not shown) adapted to accomplish rows of stitching 25—A, 27—A; and 13—A is a much larger portion of the ruffled material which is being similarly and simultaneously advanced toward the same stitching apparatus, the ruffle material being shown beneath the body fabric. As the two materials are being thus advanced, the raw edge 11—B of the body fabric which forms the flap 21—A is folded under (as shown in this view) to bring the edge of the flap 21—A into alignment with the row of stitches 25—A and the raw edge portion 13—B of the ruffle material is folded upward along the line 13—C to bring the raw edge of the flap 17—A into alignment with the stitching line 27—A, the flap 21—A of the body portion lying against the flap 17—A of the ruffle structure. As the folding of the flap 17—A over against the ruffle structure to accomplish the heading 19—A is completed, suitable tucking mechanism (not here shown), gathers the ruffle material along the stitching lines, 40 forming both a ruffled heading and a ruffled skirt, and so gathered it is secured to the flat body portion 11—A and its flap portion 21—A by the stitching and delivered from the stitching means. 45

It will be understood that the term "raw edge" 50 is here used to differentiate from a hemmed edge and may be a selvage edge of the cloth.

I claim:

An edged body fabric, comprising the fabric body and a ruffle secured thereto by a double row 55 of stitching, an edge-portion of said body, slightly

wider than the spacing of said stitching, being folded inward and forward upon itself substantially to the line of the inner of said rows of stitching; said ruffle including a heading portion superposed along an edge portion of said body, and an integral skirt portion extending beyond said edge, the edge portion of said ruffle forming said heading, lying inward of said stitching, being a substantial portion of the total width of

5 said ruffle, and being folded inward and backward upon itself with the raw edge of said fold extending substantially to the line of the outer of said rows of stitching, said ruffle being gathered along the line of said stitchings, and said stitching lines substantially concealing the edges of the folded portions of said body and ruffle.

LORANCE R. WRIGHT.
